The ornamental design for a pattern for fabrics and the like, as shown and described.

DESCRIPTION

FIG. 1 is a top plan view of the pattern for fabrics and the like;

FIG. 2 is an enlarged fragmentary perspective view of a portion of the pattern of FIG. 1;

FIG. 3 is a top plan view of a second embodiment of the pattern for fabrics and the like; and,

FIG. 4 is an enlarged fragmentary perspective view of a portion of the pattern of FIG. 3.

The broken lines define a portion of the fabric and the like and indicate that the pattern continues indeterminately in one or more directions and repeats uniformly throughout the length and width of the fabric and the like. The broken lines form no part of the claimed design.
